US0D1114172S

(12) **United States Design Patent** (10) **Patent No.:** **US D1,114,172 S**
(45) **Date of Patent:** **** Feb. 17, 2026**

(54) **SPRAY GUN BODY**

(71) Applicant: **Graco Minnesota Inc.**, Minneapolis, MN (US)

(72) Inventors: **Mark C. Richter**, River Falls, WI (US); **Dawn P. Svenkeson-Koubal**, Wayzata, MN (US); **Amelia J. Stech**, St. Paul, MN (US)

(73) Assignee: **Graco Minnesota Inc.**, Minneapolis, MN (US)

(**) Term: **15 Years**

(21) Appl. No.: **29/902,130**

(22) Filed: **Sep. 8, 2023**

Related U.S. Application Data

(62) Division of application No. 29/781,112, filed on Apr. 28, 2021, now Pat. No. Des. 1,002,805.
